ULTRA HIGH FREQUENCY OSCILLATOR

Hia E. Mouromtseff, Montclair, and George M. Dinnick, Bloomfield, N. J., assignors to Westinghouse Electric Corporation, East Pittsburgh, Pa., a corporation of Pennsylvania

Application July 18, 1941, Serial No. 402,960

8 Claims. (Cl. 250—27.5)

Our invention relates to high frequency apparatus and especially to the type of high frequency apparatus utilizing hollow body resonators.

An object of our invention is to simplify the construction of high frequency oscillators utilizing hollow body resonators.

Another object of the invention is to provide a hollow body resonator having one integral portion acting as a cathode and another integral portion acting as a grid.

Another object of the invention is to provide means for easily adjusting two resonators to oscillate at the same frequency.

Other objects and advantages of the invention will be apparent from the following description and drawing in which:

Fig. 1 is a cross-sectional view through a preferred embodiment of our invention.

Figs. 2 and 3 are views on lines II—II and III—III respectively of Fig. 1.

In Fig. 1, we have disclosed a simplified, easily adjusted and cooled ultra high frequency oscillator composed of two hollow body resonators 10 and 11 placed adjacent each other with a short space 12 therebetween. In their preferred form these resonators comprise cylindrical bodies of sheet copper 13 and 14 having frusto-conical projections 15 and 16 sloping towards each other and terminating in substantially parallel end walls 17 and 18 bounding the intervening space 12. End wall 17 is shown as perforate at least in part for passage of electrons therethrough, and consequently the perforate part may be referred to as grid 19 for resonator 10. End wall 18 similarly provides a grid 20 as part thereof for the entrance of electrons into the resonator 11.

The space 12 is field free of radio or microwave frequencies but has a high acceleration direct current field as we apply a voltage of the order of 15,000 volts to the resonator 11 and preferably keep the resonator 10 at ground potential.

Projecting within the first cylindrical body 13 is a smaller cylindrical tube 21 of copper terminating closely adjacent to the end wall 17 of the frusto-conical projection 15. This tube member 21 has its inner end closed by a plate 22 preferably coated on its outer surface toward grid 19 with an electron-emitting material such as barium, strontium, and calcium oxide, thereby constituting said plate a cathode. The grids 19 and 20 are of refractory material such as tantalum, tungsten, molybdenum or graphite and with the perforations of one aligned with perforations of the other so as to intercept a minimum of electrons. The oxide coating on the plate 22 may be in islets cor-

responding in alignment with the openings in the grids. The space between the cylindrical side 13 of this resonator 10 and the tube member 21 is closed by a flexible sheet or diaphragm 23 joined, as by silver solder, at 24 to the outer cylindrical surface 13 and also silver soldered at 25 to the tubular member 21. This flexible sheet 23 has corrugations 26 therein in order to move easily with the adjustment of the position of the tubular member 21.

Within the tubular member 21 and closely adjacent the electron-emitting plate or cathode 22, is a heater 27 with conductors 28 passing through a press 29 to the exterior of the device. The press 29 is sealed into a ring 30 of iron-nickel-cobalt alloy, preferably that sold under the trade name of "Kovar," and this "Kovar" is preferably welded to a ring 31 of steel, that is preferably silver soldered to the inner cylindrical surface of the end portion of the tube 21. This steel ring 31 preferably has an extension 32 which is screw threaded on its outer surface to receive a cap 33 enclosing a double ring and ball bearing arrangement 34, 35 and 36, with the outer ring 34 bearing against the cap 33, and the inner ring 36 secured to a shaft 37 extending to an adjusting handle 38. The shaft 37 and adjusting handle 38 have a central opening therethrough for the heater connections 28. A skeleton cylindrical casing 40 is attached to the cylindrical edge 13 of the resonator 10 and encloses the exterior portion of the tube member 21 and the ball bearing adjustment. The skeleton casing comprises a ring 41 and two arms 116 and 117 supporting an arm 42 extending across the diameter thereof, to provide a screw threaded fulcrum for the shaft 37. The position of the electron-emitting plate 22 in regard to the grid 19 at the end wall 17 of the first resonator 10 is adjusted by the handle 38 acting through the shaft 37, ball bearing arrangement 34, 35 and 36, steel ring 32 and tubular member 21. We preferably cover the outer portion of the tubular member 21 with copper fins 43.

Projecting within the cylindrical body 14 of the second resonator 11 is a copper cylinder or collector 50 having its inner edge 51 closely adjacent the grid 20 in the frustum end wall 18. This copper cylinder has an opening 52 therein which is preferably of considerable diameter at the beginning of the opening 53 and then gradually tapers into a gentle, conical slope 54 to a gently curved bottom 55. In the first part of this opening at 53 are placed a grid 56 and preferably two or more grids, such as 57 and 58 illustrated. These grids may take the form disclosed in Fig. 2 in which

U-shaped members 60 are having a long leg 61 extending almost to the axis of the opening, and the other leg 62 shortened to occupy the space intermediate the long leg 61 of this particular grid member, and the long leg of the next grid member 60. The annular positions of these long legs of the three grids are preferably oriented a few degrees such as six degrees from one another to prevent electrons, either primary or secondary, from passing from the opening 52 back into the resonator 11. A flexible copper sheet 65 with grooves or corrugations 66 is joined, as by silver soldering, to the outer cylindrical edge 14 at 68 and also is preferably silver soldered at 69 to the outer surface of the copper cylinder 50. The copper cylinder at its exterior end 70 has secured thereto, a cap 71 enclosing an outer ring 72, ball bearings 73 and inner ring 74 to a shaft 75. This construction is similar to that of 34, 35 and 36 at the other end of the casing. A skeleton housing 76 has a cylindrical ring 77 that is attached to the cylindrical edge of the second resonator 11. This skeleton housing may be merely a couple of arms 120, 121 extending from diametric opposite portions of the ring 77 for supporting an arm 78 extending thereacross, similar to the arm 42, to provide a fulcrum for the screw threaded shaft 75. An adjusting handle 79 is secured on the shaft 75, where it projects from the casing 76. The adjusting handle 79 moves the cylindrical copper member or collector 50, and this adjusts the position of the first grid 56 in relation to the grid 20 in the end wall of the frusto-conical projection of the resonator 11. The cylindrical copper member 50, where it emerges from the resonator 11, is preferably surrounded by fins 80, and these may be annular fins bound by spacing rings 81 to the outer surface of this copper cylinder 50. The skeleton housing 76 permits adequate cooling of the fins 80 by a fan or other means.

The space between the two resonators, may be peripherally enclosed in any desired manner, and we have disclosed a particular advantageous form in which two rings 90 and 91 slightly larger than the diameter of the frustum of the cones have one edge 92 and 93, respectively shaped to fit the conical sloped sides 15 and 16. These rings are joined as by soldering, to the conical sides 15 and 16. U-shaped members 94 and 95 preferably of iron-nickel-cobalt alloy sold under the trade name of "Kovar," have one of their edges 96 and 97, respectively, soldered to a surface of the rings 90 and 91, and have their outer edges 98 and 99, respectively cemented into the edges of a doughnut-shaped glass casing 100. This doughnut-shaped glass casing has a tubulation 101, whereby the space and the interior of both the resonators 10 and 11, can be evacuated. This glass casing permits the higher voltage of the order of 10,000 volts or more or less to be applied to the second resonator 11 above that applied to the first resonator.

In order to provide a feed-back arrangement to adjust the oscillations of the two resonators in both phase and amplitude, we provide preferably the feed-back arrangement 102 illustrated, although other types may be utilized. This feed-back arrangement preferably comprises interior loops 103 and 104 in the two resonators 10 and 11, respectively. One end of the loop is secured to the casing, and the other end of the loop passes through openings 105 in the casing and axially through a sleeve 106 of the iron-nickel-cobalt alloy sold under the trade name of "Kovar," which is soldered, preferably with silver, to the copper casing. Insulation such as borosilicate glass 107,

closes the outer end of the "Kovar" eyelet, except for the loops 103 and 104 passing therethrough to terminate in exterior loops 108 and 109, secured at its other end to the eyelets 106. Intermediate the exterior loops 108 and 109 is a concentric transmission line preferably composed of an axial conductor 110 and an enclosing cylindrical casing 111 having a loop 112 adjacent the exterior loop 108 and another loop 113 adjacent the loop 109. The length of the transmission line 110, 111 and the planes of the two pairs of loops 108, 112 and 109, 113, can be adjusted to provide control of the amplitude and phase of the oscillations in the two hollow body resonators 10 and 11. The output of the hollow body resonator 11 may be taken off of the loop 109 by a similar loop 114 connected to a concentric transmission line 115. If desired, however, a separate output arrangement similar to the feed-back loops 104 and 109, may be located on another portion of the resonator 11 to provide an output to feed the loop 114 and transmission line 115. If desired, additional loops may be applied to either or both resonators to feed in oscillations, preferably at microwave frequencies, to the resonators.

In operation electrons will be released from the plate or cathode 22 by the action of the heat from the heater wire 27. The hollow body resonator 10 will be adjusted to resonate, preferably at microwave frequency, in relationship to the hollow body resonator 11 by the feed-back arrangement 102. These oscillations of the hollow body 10 will produce a varying polarity at opposite portions of the casing. The plate 22 with one swing of the oscillations will be a negative polarity and will act as a cathode. End wall 17 at the same instant will be positive in regard to the oscillation swing, and this will permit the electrons to pass through the grid 19 into the space 12. This space 12 is field free of radio or microwave frequency but has a strong D. C. field. Because of the extremely high frequency of the oscillations, the electrons from the plate 22 will pass into the space 12 during a very brief half cycle and then be blocked by the opposite swing of the oscillations making the grid 19 negative and the plate 22 positive. The high D. C. field from the resonator 11 will pull these electrons through the space 12 in bunches and the electrons will then enter through grid 20 in the end wall 18 still bunched. The transmission line 102 is adjusted so that these electrons enter the resonator 11 in opposition to the field and will give up their energy or a large portion of it to the resonator 11. The electrons will pass through the various grids 56, 57 and 58, and will be scattered along the gently tapered side 54 of the opening 52. This scattering will prevent any local overheating of the interior surface of the copper cylinder 50. A target, preferably of tungsten, may replace the collector 50.

It will be noted that the hollow body resonator 10 is an integral operating unit and yet has one portion thereof namely the plate 22, acting as a cathode, and another integral portion, namely a part of end wall 17, acting as a grid. This construction eliminates the separate provision of cathode and grid which were heretofore thought necessary.

It will be also noted that the construction illustrated, provides a ready means for replacing the heater wire 27 which is one of the first elements that may need to be replaced, and that this can be done without disturbing the vacuum of the hollow body resonator 10. The loosening of the arm 42 from the cylindrical casing 40, and the

unscrewing of the ring 31 from the inner surface of the tubular member 21 will remove the heater wire from the inner portion of the tubular member 21 for repair or replacement.

While we have disclosed a preferred embodiment of our invention, it is apparent that many modifications may be made therein and, accordingly, we desire only such limitations to be imposed upon our invention as is necessitated by the spirit and scope of the following claims.

We claim:

1. A hollow body resonator comprising a metal casing having at its rear end a flexible metal sheet, a metal tubular member projecting through said sheet, an electron emitting plate at the end of said tubular member, the forward end wall of said casing opposite said plate having an opening for the passage of electrons therethrough, and the side wall of said casing being a rigid metallic body of revolution.

2. A hollow body resonator comprising a metal casing having on one side a flexible metal sheet, a metal tubular member projecting through said sheet, an electron emitting plate at the end of said tubular member, the wall of said casing opposite said plate having an opening for the passage of electrons therethrough, a press of insulation within said tubular member, means sealed to said press and attached to said tubular member enclosing a space therein, a heater in said space and leads for said heater sealed through said press.

3. A hollow body resonator comprising a metal wall having an opening therethrough, a metal block having one face parallel with said opening, said metal block having an electron receiving cavity in said face and a flexible metal sheet interconnecting said block and said wall.

4. A hollow body resonator comprising a metal wall having an opening therethrough, a metal block having one face parallel with said opening, said metal block having an electron receiving cavity in said face and a flexible metal sheet interconnecting said block and said wall at an intermediate portion of said block, the outer portion of said block having fins attached thereto.

5. A hollow body resonator comprising a metal wall having an opening therethrough, a metal block having one face parallel with said opening, said metal block having an electron receiving cavity in said face and a flexible metal sheet

interconnecting said block and said wall, a casing connected to said wall and flexible metal sheet and adjusting means connected to said block and based on said casing for positioning the face of said block in relation to said opening.

6. A hollow body resonator comprising a metal wall having an opening therethrough, an electron emitting plate parallel to the opening in said metal wall and a flexible metal sheet interconnecting said plate and said metal wall, a casing connected to said wall and flexible metal sheet and adjusting means connected to said plate for positioning the plate in relation to said opening.

7. A hollow body resonator comprising a metal casing having a rear end wall comprising a flexible metal sheet, a metal tubular member projecting through said sheet, an electron emitting plate at the end of said tubular member, said casing having a forward metallic end wall opposite said flexible rear wall, said forward wall having an opening for the passage of electrons therethrough, a side wall comprising a rigid metallic body of revolution connected to said forward end wall and to said flexible rear end wall, the several said walls and emitting plate thereby forming a hollow resonant body, and adjusting means connected to said tubular member and to said side wall for positioning the plate in relation to said opening.

8. An electronic device comprising two resonators having spaced frusto-conical portions extending toward each other, the two ends toward each other of said frusto-conical portions having two ends parallel to and toward each other and having openings therethrough whereby said ends constitute grids as parts of the walls of the resonators, the grid of one frusto-conical portion giving entry to one resonator and the grid of the other frusto-conical portion giving entry to the other resonator, means enclosing vacuum tight the space between said two ends, said means comprising insulation electrically separating the resonators, means forming part of the wall of one resonator and constituting a cathode, and means forming part of the wall of the other resonator and constituting a collector, said cathode and collector means being opposite each other with said two grids therebetween.
